(57) **CLAIM**

The ornamental design for an elongated diffuser with speakers as shown and described.

DESCRIPTION

FIG. 1 is a perspective view of an elongated diffuser with speakers, showing a first embodiment of our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and

FIG. 7 is a bottom plan view thereof.

FIG. 8 is a perspective view of an elongated diffuser with speakers, showing a second embodiment of our new design;

FIG. 9 is a front view thereof;

FIG. 10 is a rear view thereof;

FIG. 11 is a right side view thereof;

FIG. 12 is a left side view thereof;

FIG. 13 is a top plan view thereof; and,

FIG. 14 is a bottom plan view thereof.

The broken lines shown in the Figures show portions of the elongated diffuser with speakers that form no part of the claimed design and are for illustrative purposes only.

The shade lines in the Figures show contour and do not claim surface ornamentation or treatment.
